UNITED STATES PATENT OFFICE.

JOHN D. FEE, OF CHICAGO, ILLINOIS.

RUNNING-GEAR OF RAILWAY-CARS.

SPECIFICATION forming part of Letters Patent No. 245,920, dated August 16, 1881.

Application filed May 25, 1881. (No model.)

To all whom it may concern:

Be it known that I, JOHN D. FEE, a citizen of the United States, residing at Chicago, in the county of Cook and State of Illinois, have 5 invented certain new and useful Improvements in Running-Gear of Railway-Cars; and I hereby declare the following to be a full, clear, and exact description thereof, reference being had to the accompanying drawings, of which—

10 Figure 1 is a plan view of my improvement; Fig. 2, a vertical longitudinal section of the same; Fig. 3, a central cross-section of the same, and Figs. 4 and 5 detail views.

15 My invention relates to mechanism for permitting cars having a third or central truck to turn curves without additional friction between the wheels and rails. It is well known that with all cars, but especially with those of the increased length now coming extensively into 20 use, this friction is very great, and that the problem of lessening it, with its attendant flange wear, heavy draft, and destructive strain upon the track and rolling-gear is one of serious concern.

25 A general idea of the nature of my invention and in what it consists may be gathered from the following brief outline: I provide for each car a rectangular base-frame, generally of iron, upon which the body of the car rests, and crossing 30 this frame on its lower side and rigidly secured to it are three strong transoms of iron, or wood, or both, one at the center and one toward each end. These transoms form the supports for all the remaining parts, embracing the 35 trucks and the actuating mechanism. Upon the lower side of the central transom is a plate corresponding with the same in area and adapted to slide upon it, within prescribed limits, in 40 guides. To this sliding plate a central truck is suspended. A reach, to which the draw-bar is attached, extends from end to end of the frame, but is formed in two parts, being divided at the center of the car. Each part of the reach is pivoted to the lower side of the sliding 45 plate at the center, and also to the lower side of one of the transoms near the ends of the frame. To each half of the reach is rigidly secured a device analogous to the hounds of a 50 wagon, and to these hounds are suspended the end trucks. The hounds, moreover, are diagonally connected together by truss-rods.

As a result of this construction the act of turning a curve throws the inner ends of the reach to one side, carrying with them the central truck, and at the same time this movement on the part of 55 the reach so turns the hounds as to cause each axle to occupy the position, or nearly the position, of a radius to the curve. The shifting of the central truck, and the turning just described of the axles, so as to occupy the position of 60 radii to the curve, constitute the leading objects of my invention.

In addition to the foregoing, my invention consists in various details of construction and combinations of parts, all as hereinafter more 65 fully set forth.

Referring to the drawings, A is the rectangular frame, hereinbefore referred to, which I usually make of the length of the car and about the width of the trucks; B B, the two transoms near the ends of the same, and B' the central transom. Each of these is rigidly secured to the frame A by means of bolts v, or in any other effective manner.

C is the truck-bolster upon the lower side of 75 the central transom, and sliding within guides u, projecting downward from the said transom. In order to lessen the friction incident to this sliding movement I provide the transom B' with rollers or wheels t, as shown in 80 Fig. 3. To this bolster are suspended the central truck-pedestals D.

E is the reach, formed in two parts, meeting at the center of the car below the sliding plate C, and connected thereto by means of stirrups 85 s, adapted to afford them the requisite pivotal motion. Each half of the reach is also firmly pivoted to one of the transoms B by means of a bolt, r, or other analogous device.

F F are the hounds, strongly secured one to 90 each half of the reach. Each hound is bolted at one end to the reach, as shown at g, and is maintained in a plane parallel with the reach by resting at its opposite end in a bend, p, formed in the said reach. The inner corners of both 95 hounds are diagonally connected together by truss-rods G G, crossing each other at the center. It is necessary that these rods have a pivotal motion upon the hounds which they connect, in order not to interfere with the action 100 of the reach. I accordingly provide them with forked ends o, as shown in Fig. 5, adapted to

fit above and below the hound, and secure them in place thereto by bolts v' . Each hound is firmly bolted to the bolster B^2 , to which the pedestals of the end trucks are attached. As a result of the foregoing construction, while the car is on a straight track the reach maintains a central position, as represented by the full lines in Fig. 1. In turning a curve, however, instead of occupying the position of a cord to the arc of the curve, it is forced together, with the hounds, into an oblique position across the pivotal points in the transoms B , thus throwing the central truck outward and turning the end trucks to the positions of radii to the curve, all as indicated by the dotted lines in said figure. The function of the truss-rods G is not in any way to modify or aid in producing the above effects, but only to compensate in the matter of strength for the brake at the center of the reach without impeding the operation of the latter.

The drawings represent two-wheeled trucks only; but it is obvious that all that has been said is equally applicable to four and to six wheeled trucks.

What I claim as new, and desire to secure by Letters Patent, is—

1. In a railway-car, the combination of a central truck adapted to slide laterally within prescribed limits beneath the body of the car, two end trucks pivotally attached to the body of the car, whereby they may be turned to oblique positions with respect to said body, and a reach formed in two parts, extending from the central truck toward opposite ends of the car in line with the draw-bar, each of said parts being rigidly connected by suitable bracing mechanism to one of the end trucks and pivotally connected to the central truck, substantially as described.

2. The combination of the rectangular frame A , end transoms, B , and central transom, B' , bolster C , sliding in guides on the lower face of the transom B' and carrying the center truck, reach E , made in two parts, as shown, and pivotally connected to the sliding bolster C and to the end transoms and hounds, F , carrying the end trucks, and rigidly secured one to each part of the reach E , substantially as described.

3. In combination with the rectangular frame A , transoms B and B' , sliding bolster C , carrying the center truck, centrally-divided reach E , pivotally connected to the sliding bolster C and to each of the end transoms, B , and hounds F , carrying the end trucks, and each rigidly secured to the reach, the diagonal truss-rods G , connecting the opposite inner corners of the hounds, substantially as described.

4. The combination of the rectangular frame A , end transoms, B , central transom, B' , provided with friction rollers or wheels t , and guides u , bolster C , lying against the friction-rollers t and sliding in the guides u , and carrying the central truck, reach E , divided at the center, with its inner ends sitting within stirrups s on the sliding bolster C , and pivotally connected to the end transoms, B , hounds F , each firmly bolted to the reach E and to the bolster B^2 of the end trucks, and diagonal truss-rods G , pivoted to the opposite inner corners of the hounds, substantially as described.

JOHN D. FEE.
